UNITED STATES PATENT OFFICE.

WILL CAMERON McCARTNEY, OF CAMBRIDGE, OHIO, ASSIGNOR TO THE CAMBRIDGE GLASS COMPANY, OF CAMBRIDGE, OHIO, A CORPORATION OF OHIO.

DESIGN FOR A GLASS GOBLET OR SIMILAR ARTICLE.

Application filed November 19, 1925. Serial No. 15,471. Term of patent 7 years.

To all whom it may concern:

Be it known that I, WILL CAMERON McCARTNEY, a citizen of the United States of America, and resident of Cambridge, county of Guernsey, and State of Ohio, have invented a new, original, and ornamental Design for a Glass Goblet or Similar Article, of which the following is a specification, reference being had to the accompanying drawings, in which the figure is a side elevation of a glass goblet, showing my new design.

I claim:

The ornamental design for a glass goblet or similar article, as shown.

WILL CAMERON McCARTNEY.
